(57) **CLAIM**

The ornamental design for a boat helm, as shown and described.

DESCRIPTION

FIG. 1 is a rear left side perspective view of a boat helm according to the new and ornamental design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines shown in the drawings illustrate portions of the boat helm and forms no part of the claimed design. The dash-dot-dash lines define the bounds of the design and forms no part of the claimed design.

1 Claim, 7 Drawing Sheets
